US00D858731S

(12) **United States Design Patent** (10) Patent No.: **US D858,731 S**
(45) Date of Patent: ** Sep. 3, 2019

(54) **FILTER FOR AIR PURIFIER**

(71) Applicant: **LG ELECTRONICS INC.**, Seoul (KR)

(72) Inventors: **Chinsoo Hyon**, Seoul (KR); **Seungho Baek**, Seoul (KR); **Yunseo Jang**, Seoul (KR); **Jaeyeong Jo**, Seoul (KR)

(73) Assignee: **LG Electronics Inc.**, Seoul (KR)

(**) Term: **15 Years**

(21) Appl. No.: **35/504,878**

(22) Filed: **Nov. 9, 2017**

(80) **Hague Agreement Data**

Int. Filing Date: **Nov. 9, 2017**

Int. Reg. No.: **DM/099370**

Int. Reg. Date: **Nov. 9, 2017**

Int. Reg. Pub. Date: **May 11, 2018**

(30) **Foreign Application Priority Data**

May 10, 2017 (KR) 30-2017-0020943

(51) **LOC (12) Cl.** **23-04**

(52) **U.S. Cl.**

USPC **D23/365**

CPC **A61L 9/00** (2013.01)

CLAIM

The ornamental design for a filter for air purifier, as shown and described.

DESCRIPTION

1. Filter for air purifier

1.1 : Perspective

1.2 : Front

1.3 : Back

1.4 : Left

1.5 : Right

1.6 : Top

1.7 : Bottom

1.8 : Reference

1.9 : Reference

The broken line showing of an air purifier in Reproductions

1.8 and 1.9 is for the purpose of illustrating environmental structure of the filter for air purifier and forms no part of the claimed design. Reproduction 1.8 is a reference view showing the subject design installed in an air purifier; reproduction 1.9 is a reference view showing the subject design separated from an air purifier.

1 Claim, 8 Drawing Sheets
